US0D1085194S

(12) **United States Design Patent** (10) **Patent No.:** **US D1,085,194 S**
(45) **Date of Patent:** **** Jul. 22, 2025**

(54) **LED EYEWEAR**

(71) Applicant: **Lumileds LLC**, San Jose, CA (US)

(72) Inventors: **Brendan Moran**, San Jose, CA (US);
Mukul Agrawal, San Jose, CA (US);
Zhongmin Ren, San Jose, CA (US)

(73) Assignee: **LUMILEDS LLC**, San Jose, CA (US)

(**) Term: **15 Years**

(21) Appl. No.: **35/520,911**

(22) Filed: **May 13, 2023**

(80) **Hague Agreement Data**

Int. Filing Date: **May 13, 2023**

Int. Reg. No.: **DM/232911**

Int. Reg. Date: **May 13, 2023**

Int. Reg. Pub. Date: **May 17, 2024**

(51) **LOC (15) Cl.** **16-06**

(52) **U.S. Cl.**

USPC **D16/101**

(58) **Field of Classification Search**

USPC D16/300-342, 101; D14/372
